PANELING FOR LIGHTING FIXTURES

Richard S. Hawes III, Mosley Road, Creve Coeur, Mo.,
and Frederick L. Hawes, 16 Enfield Road, Olivette, Mo.

Filed Feb. 24, 1959, Ser. No. 54,703

Term of patent 14 years

(Cl. D48—16)

FIG. 1

FIG.2

FIG.3

FIG.4

FIGURE 1 is a top plan view of paneling for lighting fixtures, showing our new design, with portions shown broken away to indicate indeterminate length;

FIGURE 2 is an enlarged fragmentary top plan view of a border area of the panel shown in FIGURE 1;

FIGURE 3 is a fragmentary sectional view taken along the line 3-3 of FIGURE 2; and

FIGURE 4 is a fragmentary sectional view taken along the line 4-4 of FIGURE 2.

We claim:

The ornamental design for paneling for lighting fixtures, as shown and described.
